(57) **CLAIM**

The ornamental design for a jacket as shown and described.

DESCRIPTION

1. Jacket
  2. Jacket
  3. Jacket
  1. Jacket.
  - 1.1 Front.
  - 1.2 Rear.
  - 1.3 Left.
  - 1.4 Right.
  - 1.5 Top
  - 1.6 Bottom.
  - 1.7 Front with collar separated.
  2. Jacket.
  - 2.1 Front with collar removed
  - 2.2 Rear.
  - 2.3 Left.
  - 2.4 Right.
  - 2.5 Top.
  - 2.6 Bottom.
  - 2.7 Front with collar separated.
  3. Jacket.
  - 3.1 Front.
  - 3.2 Rear.
  - 3.3 Left.
  - 3.4 Right.
  - 3.5 Top.
  - 3.6 Bottom.
  - 3.7 Front with collar separated.
- The torso part and the collar part are separated; design 1: both parts are attached by buttons and buttonholes; design 2: both parts are attached by snap buttons; design 3: both parts are attached by hook and loop fasteners; reproductions 1.1 to 1.6, 2.1 to 2.6 and 3.6 show a part of the jacket which is (Continued)

part of the claimed design; reproductions 1.7, 2.7 and 3.7 show the jacket with a removable collar which is part of the claimed design. The broken lines on the jacket and removable collars depict portions of the garment that form no part of the claimed design.

1 Claim, 21 Drawing Sheets
